RIVETING TOOL

Raymond E. Nelson, Seattle, Wash.

Application December 22, 1941, Serial No. 424,040

1 Claim. (Cl. 78—53.5)

My invention relates to the art of riveting and has among its objects and advantages the provision of an improved rivet tool.

Riveted joints are frequently defective because of the fact that the members riveted together are not drawn into firm engagement one with the other. In forming the rivet head, the rivet tends to swell. Unless the members riveted together lie in firm engagement one with the other, such swelling swells between the spaced members of the work and results in a defective joint, since the members of the work can not be drawn into firm engagement.

Accordingly, an object of my invention is to provide a riveting tool so designed as to bring the members of the work into firm engagement one with the other and simultaneously swell the rivet so as to hold the work members in firm engagement until the rivet head is formed.

In the accompanying drawing:

Figure 1 is a longitudinal sectional view illustrating my invention;

Figure 2 is an elevational view of a plunger;

Figure 3 is an elevational view of the tool;

Figures 4 and 5 are sectional views taken along the lines 4—4 and 5—5 of Figures 1 and 3, respectively; and

Figure 6 is a modified form of the invention.

In the embodiment selected for illustration, I make use of a tubular body 10 within which is loosely mounted a hammer 12. Body 10 is constricted to provide a smaller diameter tubular neck 14, and the hammer 12 is provided with a body 16 fitting loosely in the larger diameter portion 18 of the body 10. A shaft-like hammer end 20 is provided on the body 16, which hammer end fits loosely inside the neck 14. Thus the hammer 12 includes a shoulder-like formation 22 arranged to abut the taper 24 connecting the portions 14 and 18 of the body 10.

Between the body portion 16 and a plug 26 is interposed a compression spring 28. Plug 26 is provided with a threaded shank 30 threaded into the internally threaded body portion 18. A set screw 32 is threaded into the body portion 18 for engagement with the shank 30 to prevent accidental loosening thereof. Figure 1 illustrates the rivet-engaging end 34 of the hammer end 20 as terminating slightly inwardly of the work-engaging end face 36 of the neck portion 14. The work-engaging end of the neck portion is preferably provided with a flange 38 to increase the area of the face 36.

In operation, the rivet 40 is placed in position in the aligned openings in the work members 42 and 44. The head 46 of the rivet lies adja-

cent the member 44 and the other end of the rivet extends into the bore 48 of the neck portion 14. A bucking bar is held in engagement with the plug 26 and a riveting hammer is applied to the head 46. Blows effective on the rivet head 46 drive the members 42 and 44 into firm engagement one with the other, since the face 36 engages the member 42. At the same time, the hammer end 20 is maintained in engagement with the rivet 40 by reason of the spring 28. Such engagement between the hammer end and the rivet imparts swelling distortion to the rivet for firmly securing the members 42 and 44 in engagement. Spring 28 is of sufficient tension to hold the hammer end firmly against the rivet, although the hammer 12 is driven inwardly of the body 10 at each blow of the rivet hammer but the spring 28 returns the hammer 12 into engagement with the rivet before the next air hammer blow is struck.

When once the rivet 40 has been swollen to bring the members 42 and 44 into firm engagement, the rivet head may be formed in the usual manner. The tool is designed in different sizes to handle rivets of variable sizes.

In Figure 6, I illustrate the bore 50 corresponding to the bore 48 as being flared to provide accommodation for dimpled metal, wherein laterally offset margins of the work have interfitting engagement.

Without further elaboration, the foregoing will so fully illustrate my invention, that others may, by applying current knowledge, readily adapt the same for use under various conditions of service.

I claim:

A riveting tool comprising a tube, a tubular axial neck at one end of said tube of smaller inside diameter than the tube providing a shoulder between the tube and the neck, said neck having a work engaging face circumjacent the opening in the neck to engage the work circumjacent a rivet extended through the work and into the opening, a rivet hammer inside the tube movably guided thereby and having a pin extending into said neck for end engagement with the rivet, said hammer having a shoulder engaging said first-mentioned shoulder to position the end of the pin a predetermined distance from said face, a closure for the other end of the tube, and a compression spring interposed between the hammer and said closure to yieldingly hold the pin in engagement with the rivet, said spring normally holding said second-mentioned shoulder in engagement with said first-mentioned shoulder.

RAYMOND E. NELSON,
